UNITED STATES PATENT OFFICE

JACOB G. PECK, OF PORTLAND, OREGON

ACCUMULATOR CONTAINER IN EXPANSION COILS

Application filed December 23, 1925. Serial No. 77,239.

This invention relates to my pending applications in the United States Patent Office, as evidenced by the following:

Ice cream cabinet and means for automatically maintaining more than one temperature therein simultaneously, filed January 9, 1925, Serial No. 35,996.

Refrigerator for two temperature cabinet, filed August 5, 1925, Serial No. 48,376.

10 New and improved two temperature refrigerating and cooling cabinet, filed August 5, 1925, Serial No. 48,377.

Process for circulating a refrigerant in a two temperature cabinet, filed August 5, 1925, 15 Serial No. 48,374.

The primary object of my present invention is to increase the storage supply of refrigerant material within the system and at the same time to place the storage accumulators at such locations in the system that the liquid refrigerant material may be trapped within the accumulators, thus preventing the same from being returned, back to the refrigerating machine, as a liquid.

20 Further objects of my present invention consists in placing the accumulator containers in such a position within the circuit of the refrigerating expansion coil that the accumulator containers will act as traps for the trapping of foreign substances that may get into the stream flow of the refrigerant and be carried into the valves, or into the machine, such foreign substances consist of scale, or sedimental deposits, oil, water and other elements.

Still further objects of my present invention consist in the placing of the accumulator containers in position within the insulation in order that the temperature of the refrigerant material within the accumulator containers will be maintained at the minimum temperature.

40 The accumulator containers act as a surplus storage supply for the refrigerant material, and as the normal requirement becomes depleted from leakage or other causes, within the expansion coils, the surplus within the accumulator containers will expand and be used, thus acting in effect as automatic feeding of the surplus refrigerant, for

use as a refrigerating medium, back into the expansion coils as an active agent.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

Fig. 1 is a top plan view partially in section of one of my new and improved two temperature cabinets, illustrating the location of the containers for the liquid and illustrating the same in position within the two temperature cabinet within the insulation and entirely surrounded by the insulation material.

Fig. 2 is a perspective view of the cooling system, as used in my two temperature cabinet, illustrating the containers to be used and the location of the same.

Fig. 3 is a cross section view, taken on line 3—3, of Fig. 1, looking in the direction indicated.

Like reference characters refer to like parts throughout the several views.

1 is the cabinet case, having lids or closures 2 provided for each of two compartments formed therein which are shown at 4 and 5; and which compartments are to be maintained at unequal temperatures. These compartments have tanks 6 and 7 forming the side walls thereof. The opposite walls of the tanks are spaced apart sufficiently to allow the passage of an expansion coil therebetween. These tanks are made sufficiently large to hold a cooling medium, such as brine, in addition to said coils. The tanks 5 and 6 are covered by insulating material sufficient to properly insulate the inner compartment and the tanks from the exterior. Figs. 1 and 3 partly show how the insulating material and its disposal about the tanks. However, the construction of the cabinet does not necessarily have to be limited to that shown, as my invention is applicable to other forms of cabinets, and in describing my invention I use the cabinet 100

and expansion coil construction here shown as a preferred construction.

In the expansion coil construction shown in Fig. 2 of the drawings, the inlet or expansion end of the coil is shown at 8. The single system of the coil expansion comprises the coil leading from the expansion valve (not shown), the accumulator 9 which it enters, the coilage that leads from the accumulator and enters the tank 6 making a turn within the tank as shown at 10a, and then passes between the insulation making two more turns, and then down to the lowest part of tank 7 as shown at 11. At this point the single system ends and the compound system begins. The coil is then wound upwardly until it reaches the top of tank 7. The coil then leads into accumulator 12; the coilage then leads from the accumulator, enters tank 6, makes a number of turns and then returns to the suction side of a compressor (not shown). I wish it to be particularly understood in my description of the disposal of the expansion coilage in the two compartments, that the coil as it is carried about each compartment, is disposed within the brine or cooling medium tank of each compartment.

In the preferred form of cooling cabinet heretofore shown as well as in other types there is a constant drain or leakage of the refrigerant material used therein, which requires frequent recharging of the device. I have found in an automatic controlled machine that when the machine has been freshly charged with refrigerant material, that a steadier temperature is maintained than when the machine has been operating over a period of time, and there has been a drain or loss of the refrigerant material. I have also found that if the actual charge of refrigerant material required to run the machine be increased for an instance, to at least two to three times the normal amount required, or, in other words, if a reserve supply of refrigerant is supplied in addition to the actual amount required to run the machine, that an irregular or uneven running of the machine will be obviated, and that the temperature will be maintained almost constant.

In Fig. 2, 9 and 12 represent my accumulator containers or reserve refrigerant tanks. The structure of these two tanks is the same, and each consists of a cylindrical container closed at each end. Each container is mounted vertically, and is preferably positioned in or surrounded by insulating material, as shown in Figs. 1 and 3. The expansion coil communicates with each of these tanks at diametrically opposite points adjacent the top thereof. I have here shown two tanks, 9 and 12, though I have had excellent results when I have used but one tank, the tank 9.

As will be seen by reference to Fig. 2, the tank 9 communicates with the expansion at a point near the expansion end of the same. The tank 12 communicates with the expansion coil at a point near the compression end of the same, and I have here shown it connected to the coil as it passes from the compartment 5 to its final turn about compartment 4 prior to passing to the compressor.

I have described in the last paragraph the structure of what I have termed "accumulator containers". I have found that in a refrigerating device of the character described which is ordinarily charged with one and one-half to two pounds of refrigerant material, such as methyl-chloride; but a device of the same character provided with my accumulator containers, may be charged with from four to four and one-half pounds of refrigerant material. This will allow a change of from two to two and one-half pounds as replacement of the refrigerant material draining or leaking from the machine over a period of time. I wish it to be particularly understood that these containers do not or are not intended to act as an extension to the expansion coilage; but are primarily intended as pockets or containers, communicating with the coils, to hold a surplus supply of the refrigerant material. I encase these containers in insulating material, as I have found that the best results are obtained when the containers are not subjected to continuous or abrupt changes of temperature.

I am aware that accumulators have heretofore been placed within the expansion coil of a refrigerating machine, but the same has been placed therein for a different purpose and at a different location within the system.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. A device of the character described, for an expansion coil embodying a single and a compound series of convolutions comprising a container communicating with said coil in advance of the first stage of the compound convolution; said container having diametrically opposite portions of its side wall adjacent its upper end communicating with said coil; and said cylinder being adapted to complement the refrigerant capacity of said coil.

2. A device of the character described for an expansion coil embodying a single and a compound series of convolutions; comprising a container communicating with said coil in advance of the first stage of the compound

convolution; a second cylindrical container communicating with said coil as it passes from the single series of its convolutions to the second stage of the compound convolutions; and said cylinders being adapted to complement the refrigerant capacity of said coil.

JACOB G. PECK.
